LAST

Elmer B. Grush, Beverly, Mass., assignor to
United Shoe Machinery Corporation, Paterson,
N. J., a corporation of New Jersey

Original application January 10, 1934, Serial No.
706,087. Divided and this application May 11,
1936, Serial No. 79,014

3 Claims. (Cl. 12—136)

This invention relates to lasts and is herein illustrated and described as embodied in a last from which shoes may be readily removed in accordance with a method and by means of a machine disclosed in my copending application Serial No. 706,087, filed January 10, 1934, of which this application is a division. The method and the machine disclosed in my copending application above mentioned utilize the principle of developing air pressure between the shoe and the last to urge the shoe off the last and also to distract the shoe and by reducing friction between the shoe and the last to facilitate removal of the shoe. The air pressure between the shoe and the last is obtained by admitting air through a tubular last pin and thence through passages in the last leading to various portions of the surface of the last.

It is an object of the present invention to provide an improved last suitable for carrying out the operation above described. In accordance with a feature of the invention a plurality of air ducts are formed in a last extending from the usual thimble hole to various portions of the surface of the last and a valve is provided for admitting air to each duct in turn while closing the other ducts. In the illustrated last, which is of the two-part hinged type, there is an air duct in the rear section of the last extending forwardly from the thimble hole and also an air duct in the forepart leading to the surface of the last and which, when the last is broken, constitutes a continuation of the forwardly extending duct in the rear part of the last.

Still other objects and features of the invention are set forth in the accompanying specification and claims, reference being had to the accompanying drawing, in which,

Fig. 1 is a view in side elevation, partly in section, of an improved last mounted upon a last pin;

Fig. 2 is a similar view showing the last in broken condition;

Fig. 3 is a similar view of a modified form of last;

Fig. 4 is a sectional view taken on the line IV—IV of Fig. 3; and

Fig. 5 is a plan view illustrating a detail of the forward end of the last.

In Figs. 1 and 2 is shown a last L having a shoe S thereon. This last is of the hinged type comprising heel and forepart sections connected by a hinge H. The joint faces of the heel and forepart sections are denoted by the reference characters J and J' respectively. In the heel

section of the last is the usual thimble hole 230 having a metallic lining 232 in the inner end of which is an opening 234. Also within the heel section of the last L is a valve casing 236 having a port 238 in communication with the inner end 5 of the thimble hole 230. The casing 236 has a second port 240 which is in communication with a duct 242 formed in the last and leading to the last bottom. The casing 236 extends forwardly from the locality of the ports 238 and 240, and 10 with an upward inclination relatively to the last. The forward end of the casing 236 is open and is flush with the joint face J, while the rear or inner end of the casing is closed. Within the casing 236 is slidably mounted a valve 244. A 15 compression spring 246 surrounding a stem formed on the inner end of the valve 244 is interposed between a shoulder on the valve 244 and the closed inner end of the casing 236. The spring 246 thus tends to urge the valve 244 outwardly. The valve is retained in the casing and is also held against rotation therein by a pin 248 which is secured to the casing and which extends within a slot 250 formed in the valve. Normally the spring 246 will maintain the valve 20 244 in the position indicated in Fig. 1. The valve 244 has formed within it a duct 252 which, when the valve is in this position, connects the ports 238 and 240 enabling air to flow from the thimble hole of the last into the space between the last 25 bottom and the interior of the shoe. In the forepart section of the hinged last L is a duct 254 having openings 255 at the toe end of the last and adapted when the last is completely broken as shown in Fig. 2 to communicate with a duct 30 256 formed within the valve 244. A rubber packing ring or gasket 258 surrounding the end of the duct 254 bears against the end of the valve 244 and prevents leakage of air from between the valve 244 and the duct 254. Breaking of the last 35 will cause the packing ring 258 to push the valve 244 inwardly against the spring 246. This will move the duct 252 out of register with the port 238 thereby cutting off the supply of air to the rear end of the shoe. The duct 256, however, 40 has an opening 260 which, when the valve 244 is in the position shown in Fig. 2, will be in register with the port 238 so that air will now be allowed to flow from the thimble hole of the last into the forward end of the shoe.

The operation of removing a shoe from the last L will now be described. The last is mounted in the usual way upon a last pin, which last pin, however, is tubular for the purpose of admitting compressed air, under control of the op- 50 55

erator, into the thimble hole 230 of the last. A suitable last pin, constituting a portion of the machine disclosed in the above-mentioned application Serial No. 706,087, is shown in Figs. 1 and 2 of the drawing of the present application. This last pin comprises a tube 188 which is slidably in a stationary sleeve 192, the tube 188 having an upper open end from which a flange 190 extends outwardly. The stationary sleeve 192 is mounted in a support 186. A packing sleeve or ring 194 of rubber surrounds the tube 188 and is interposed between the flange 190 and the upper end of the stationary sleeve 192. As is more fully explained in the above-mentioned application Serial No. 706,087, the tube 188 is drawn downwardly by a treadle mechanism, whereupon the flange 190 compresses the packing sleeve 194 against the upper end of the stationary sleeve 192, causing the packing sleeve to expand diametrically and grip the interior of the lining 232 of the thimble hole. The last rests upon a rubber gasket 196 on the upper end of the support 186 and surrounding the stationary sleeve 192. The treadle mechanism above referred to opens a valve which admits air under pressure through the tube 188. This air will pass through the opening 234, the port 238, the duct 252, the port 240, and the duct 242, and will develop pressure over a large area between the bottom of the shoe 30 and the bottom of the last, tending to separate the heel portion of the shoe from the last. The air will also spread into the space between the shoe upper and the last, thereby relieving friction. The heel end of the shoe in many cases 35 can be removed from the last by air pressure alone. Usually, however, it is more convenient to employ just enough pressure to enable the operator to remove the heel end of the shoe by hand with little if any resistance. In removing the 40 heel end of the shoe the operator breaks the last L' by downward pressure upon the sole of the shoe. The breaking of the last will cause the valve 244 to be shifted to close the passage of air to the heel end of the last and to admit air 45 into the forepart of the last, and the pressure of the air within the forepart of the shoe will facilitate removal of the forepart of the shoe in the same manner as has already been described with reference to the heel end of the shoe.

50 Figures 3 and 4 illustrate a modified form of last L' which may be used in the removal of shoes by air pressure alone, or by air pressure in conjunction with a shoe-removing machine. The last L' is of the hinged type. Formed in its heel portion is a duct 164 one end of which communicates with the thimble hole and the other end of which leads to the bottom surface of the heel portion of the last. A branch duct 166 leads from the duct 164 to the rear end 55 surface of the last at a locality adjacent to the last bottom. Another duct 168 leads forwardly from the thimble hole, and when the last is completely broken, as shown in Fig. 3, the duct 168 communicates with a duct 170 formed in the forward section of the last and terminating through three diverging branches 172 in openings in the toe portion of the last. This arrangement of the forepart ducts, as illustrated in Fig. 5, is preferably employed also in the last L, already 60 described. A rubber gasket 174 secured in the forward section of the last is compressed when the last is completely broken and prevents leakage of air from between the ducts 168 and 170. The thimble hole of the last L' is provided with 65 a metallic lining 176 in which are formed valve

ports 175 and 177 communicating with the ducts 164 and 168, respectively.

The last L' with a shoe S' thereon is mounted upon a last pin in the form of a tubular rod 88 having a passageway 110 connected to a supply of air under pressure. The upper end portion of the rod 88 is of a diameter to fit the lining 176 of the thimble hole. This end portion of normal diameter terminates in a shoulder 158 below which the diameter of the rod 88 is reduced. Surrounding the rod 88 below and in abutting relation to the shoulder 158 is a short sleeve or ring 160, preferably of rubber, adapted to fill up the space between the lining 176 and that portion of the rod 88 which is of reduced diameter. The lower end of the sleeve 160 bears against a rubber gasket 162 which rests upon a support 98 and which surrounds the rod 88. The cone of the last L' also bears upon the gasket 162. The passageway 110 within the rod 88 terminates in a pair of radially directed valve openings 178 and 179. When the last L' is mounted on the rod 88, one or the other of these valve openings may register with one or the other of the ports 175 and 177, but the angle between the valve openings is such as to prevent both valve openings being in register with both ports at the same time.

The last L', as shown in Figures 3 and 4, may be used in combination with a shoe-removing machine of the type illustrated in United States Letters Patent No. 1,820,952, granted September 1, 1931 upon the application of John Whelton and Arthur F. Pym, which shoe-removing machine has been modified as disclosed in the above-mentioned application Serial No. 706,087 to adapt it to the use of compressed air. This machine is provided with a roll 80 of rubber which is driven in a direction to raise the counterportion of the shoe S'. The support 98 above described constitutes a portion of the machine constructed and arranged for movement to bring the counterportion of the shoe into frictional engagement with the roll 80. The machine is provided with mechanism for pulling the rod 88 downward relatively to the support 98, thereby compressing the sleeve 160 longitudinally and expanding it diametrically and thus causing it to grip the interior of the lining 176. The arrangement of the valve openings 178 and 179 to the ports 175 and 177 is such that when the last L' is in position for the rear end of the shoe upper to engage the roll 80 the opening 178 will be in register with the port 175. As the shoe is being moved toward the roll, and just prior to actual engagement, air under pressure is admitted to the passage 110, and thence through the opening 178, the port 175, and the ducts 164 and 166 into the space between the heel end of the shoe and the heel end of the last. The pressure between the last bottom and the bottom of the shoe directly assists the roll 80 in removing the heel end of the shoe, while the air between the last and the shoe upper distends the shoe and reduces friction between the shoe and the last, thereby facilitating removal. The removal of the heel end of the shoe tends to break the last L', such breaking usually being assisted by the operator who presses down upon the forepart of the shoe with his hand. As already pointed out, the breaking of the last establishes communication between the duct 168 and the duct 170. Fig. 3 shows the positions of the shoe and the last just after the last has been broken. The operator will then swing the shoe about the last pin into the position shown in Fig. 4 away from the roll 80. The

turning of the last to this position will close the port 175 to the valve opening 178 and bring the port 177 into register with the opening 179, admitting air through the ducts 168 and 170 and 5 the branch ducts 172 to the toe end of the shoe. The air pressure is thus applied in diverging directions against a plurality of localities simultaneously on the interior of the toe end of the shoe upper, the effect of which is to produce momentarily a considerable expansion of the toe end of the shoe. The air not only tends to urge the shoe forwardly off the last, but also functions as a lubricant between the expanded shoe and the last to facilitate removal of the toe end of the 10 shoe from the last. The shoe may now very easily be removed from the last by hand. The support 88 is then returned to its initial position away from the roll 80, and the air supply is shut off from the passage 110.

Having thus described my invention, what I claim as new and desire to secure by Letters Patent of the United States is:

1. A two-part hinged last having a thimble hole in its rear part, from which thimble hole an 15 air duct extends forwardly, and having an air duct in the forepart of the last leading to the

surface of the last and which, when the last is broken, constitutes a continuation of the forwardly extending duct in the rear part of the last.

2. The combination of a last having a thimble hole from which a plurality of air ducts extend to various portions respectively of the surface of the last, and a valve for admitting air to each duct in turn while closing the other ducts. 5

3. A two-part hinged last having a thimble hole in its rear part, from which thimble hole extend two air ducts leading to the surface of the last in the forward and rear portions of the last respectively, the forward duct being interrupted by the break in the last when the last is 10 in normal or unbroken condition and being continuous when the last is broken, and a valve constructed and arranged when the last is in normal position to close the forward duct and to open the rear duct to the admission of air from 15 the thimble hole, said valve being also constructed and arranged when the last is broken to close the rear duct and to open the forward duct to admission of the air. 20

ELMER B. GRUSH.
